DOOR HINGE

Anestis Foltis, Jackson Heights, N. Y.

Application February 11, 1947, Serial No. 727,821

3 Claims. (Cl. 16—68)

1

This invention is an improvement in hinges for doors and other members supported to swing about vertical axes; and particularly a hinge for automatically returning a door to closed position after it has been opened.

An important object of the invention is to provide a type of hinge designed to store up energy when the door, for example, which it supports is swung aside; and to expend this energy to impel the door in the opposite direction as soon as it is released; the hinge comprising parts which preferably are designed to enclose a body of air acting as a pneumatic cushion, for retarding the reverse motion of the door to prevent jarring or slamming.

A further object of this invention is to provide a hinge of this type that is simple in its construction, certain and efficient in operation; and embracing relatively few parts, so that it can be easily and inexpensively produced.

The nature and advantages of the invention are made clear in the following specification, and the novel features are defined in the appended claims. This disclosure, however, is explanatory only, and various changes may be made in practice without deviating from the principle of the invention or exceeding its scope.

On the drawings,

Figure 1 is a top view of a hinge according to this invention in operative position.

Figure 2 is a front elevation thereof.

Figure 3 is a side elevation thereof.

Figure 4 is a section on line 4—4 of Figure 2.

Figure 5 is a horizontal section on line 5—5 of Figure 2.

Figure 6 is a vertical elevation of the construction of Figure 1, showing the parts of the hinge as they appear when the door or the like has been opened, viewed from the right of Figure 1.

Figure 6a is a detail showing a modification of the hinge.

The hinge is made up in two halves, one of which bears a tubular section or bearing 1, and the other a pair of tubular sections or bearings 2; and the halves are connected with the bearings 2 and the bearing 1 in alinement, the latter being in between the bearings 2. The bearing or section 1 is made integral with a flat leaf 3, to which it is united near the middle of one edge; and similarly the bearings 2 of the other half are united to one edge of a leaf 4. The leaf 4 is secured to the inside face of the frame or jamb 5 of a doorway, window opening or the like, and the leaf 3 of the other half is similarly affixed to the edge of the door, window or other member

2

6, which is to be mounted by means of said hinges. A part of the wall containing the doorway or window opening, is indicated by the numeral 7. Both the leaves 3 and 4 fit into recesses 5 on the adjacent faces of the frame 5 and member 6, so as to be flush with these faces when secured in position. When the door or window is closed the two halves of the hinge are in the position indicated in Figures 1 and 2, and when 10 the door or window is opened, the two halves of the hinge are unfolded or distended, as indicated in Figure 6. Inside the bearings 1 and 2 is a tubular element 8 which, among other things, serves the same purpose as a hinge pin and connects the two halves of the hinge in pivoted relation. This element 8 can turn freely in the section or bearing 1, but it is anchored and held rigid with respect to the bearings 2 by a binding screw 9 in at least one of the bearings 2. The 15 element 8 is in the form of a hollow tubular casting and also serves as a pump cylinder within which is a piston or plunger having ends 10 and 11 connected by a somewhat reduced neck 12. In the side of the part 11 of this piston is affixed a stud or screw 13 which projects out through a longitudinal slot 14 on one side of the element 8; and this stud or screw head 13 is also received in a spiral or inclined cam slot 15 in the bearing 1. Hence, whenever the bearing 1 of the hinge is turned on the element 8 as a journal, the slot 15 will cause the piston to move axially within the element 8 and this movement will carry the pin 13 lengthwise in the slot 14, and in an upward direction when the door is opened.

The one end 11 of the piston is normally disposed in the element 8 so that it lies about the middle of this element adjacent the bearing 1. The other end 10 is near the end of the element which will be the lower end when the hinge is mounted. This end carries a pair of packing rings 16 in grooved seats formed in the end 10; and this end 10 has an open recess 17 terminating in a cone-shaped seat for a ball valve 18, which is held against the seat by a suitable spring retained in the recess 17 by any suitable means. Communicating with the seat is a duct or passage 19. It leads to several ports 20, connected to the inner end of the passage 19 and all open through the lateral face of the reduced neck 12 of the piston. At the lower end the element 8 is internally threaded to receive a screw cap 21 which closes the element and the bottom of the lower bearing 2, and this cap has a small air port 22 therein. The upper end of the element and 55 upper bearing 2 are similarly closed by a screw

cap 23, which has a recess on its inner face to receive and seat a coil spring 24, which normally presses against the end 11 of the piston and tends to force the latter towards the cap 21.

When the door 6, for example, is opened as by revolving counterclockwise in Figure 1, or to the right in Figure 2, the one half of the hinge is turned so that the bearing 1 and leaf 3 revolve with respect to the bearings 2, and the slot 15 lifts the piston by reason of its action on the stud 13, which is free to slide upward in the straight slot 14 in the side of the element 8. While the piston is thus being lifted the spring 24 is compressed; and the ball valve 18 is unseated and air passes through the ports 20 and duct 19 into the lower part of the element 8 below the piston. The air in the lower part of the element 8 below the piston is rarefied somewhat when the piston moves up because the duct 22 is too small in size to permit the entrance of air rapidly enough from the atmosphere to maintain atmospheric pressure below the piston. When the piston has gone up far enough in the journal 8 so that its thinner middle part reaches and uncovers the lower end of the slot 15, air can be admitted into the space around the reduced part of the piston and this air flows through the ducts 20 and 19 and passes the valve 18 into the space below the piston in the journal 8. Hence, when the piston moves downward, there is enough air below it to cause the valve 18 to close and cushion the piston's movement and this air then escapes very slowly through the small duct 22. When the door is released the spring 24 impels the piston or plunger downward, and the action of the stud 13 on the lower inclined edge of the cam slot 15 now causes the leaf 3 of the hinge to turn towards folded position and swing the door shut. This operation is brought about very slowly, because the valve 18 is now closed and the air trapped in the lower part of the element 8 serves as a cushion or dash pot, resisting the downward motion of the piston, and is expelled little by little through the restricted opening 22. The door thus closes easily and without slamming.

Figure 6a shows a modification in which the lower cap 25 has a port 26 which communicates

with a recess 27 that has one or more passages 28 open to the atmosphere. Mounted in the bottom of this cap 25 is a pointed screw 29 by which the size of the opening 26 can be controlled.

The flat leaves 3 and 4 of the hinge can be secured to the side of the frame and the door or window by screws or the like, shown at 30.

Having described my invention, what I believe to be new is:

1. A hinge construction comprising two halves, one of which carries a cylindrical journal and the other means for pivotally connecting it to said journal, a piston in said journal, cam means carried by said other half to engage and move the piston, a spring in said journal to oppose the movement of the piston, and means for admitting air to said journal, said piston having a reduced portion between its ends, with a space between said portion and the inner surface of said journal, said piston having a valved passage in one end leading to said space.

2. The hinge construction according to claim 1, wherein said cam means comprises an inclined slot in said other half, said journal having a longitudinal slot adjacent the cam slot, and the piston carries a stud which projects in both of said slots.

3. The hinge construction according to claim 1 wherein said air inlet means comprises an inlet valve which opens upon the movement of the piston against a spring, said construction having a vent for the escape of air upon the movement of the piston in the opposite direction.

ANESTIS FOLTIS.
